William J. Roe.

C. A. Snow & Co.

UNITED STATES PATENT OFFICE.

WILLIAM J. ROE, OF FLORIDA, NEW YORK.

DESIGN FOR A CHECK-HOOK.

SPECIFICATION forming part of Design No. 24,970, dated December 10, 1895.

Application filed November 5, 1895. Serial No. 568,058. Term of patent 14 years.

To all whom it may concern:

Be it known that I, WILLIAM J. ROE, a citizen of the United States, residing at Florida, in the county of Orange and State of New York, have invented a new and original Design for a Check-Hook, of which the following is a specification.

This invention relates to a new and original design for check-hooks; and it has for its object to provide a design of this character that shall be both useful and ornamental.

The leading feature of the design resides in a check-hook provided at its closed side with an offstanding upwardly-disposed circularly-shaped figure arranged transversely to the length of the hook, said circularly-shaped figure merging into and being disposed at an acute angle to the said closed side of the hook.

In the drawings, Figure 1 is a perspective view of a check-hook embodying the design.

Fig. 2 is a side elevation thereof. Fig. 3 is a top plan view.

Referring to the accompanying drawings, the numeral 1 designates a check-hook provided with a rounded closed side 2, from which side of the hook is projected an offstanding upwardly-disposed circularly-shaped figure 3, which is arranged transversely to the length of the hook, and merges into and is disposed at an acute angle to the said closed side of the hook.

What is claimed is—

The design for a check hook herein shown and described.

In testimony that I claim the foregoing as my own I have hereto affixed my signature in the presence of two witnesses.

WILLIAM J. ROE.
